UNITED STATES PATENT OFFICE

105,220

DESIGN FOR A CLOTHES HAMPER

Paul Leverone, Arlington, Mass.

Application October 20, 1936, Serial No. 65,387

Term of patent 3½ years

To all whom it may concern:

Be it known that I, Paul Leverone, a citizen of the Republic of Uruguay, residing at Arlington, in the county of Middlesex and Commonwealth of Massachusetts, have invented a new, original, and ornamental Design for Clothes Hampers, of which the following is a specification, reference being had to the accompanying drawing, forming a part thereof.

In the drawing,

Figs. 2 and 3 are front and end views, respectively, of the hamper shown in Fig. 1.

The back and end faces of the hamper opposite to those shown in Figs. 2 and 3 are like those shown in the latter figures.

I claim:

The ornamental design for a clothes hamper, substantially as shown and described.

PAUL LEVERONE.
